CHOKE REGULATOR

Thomas N. Coffelder, Pittsburgh, Pa.

Application November 29, 1929, Serial No. 410,297

2 Claims. (Cl. 261—52)

This invention relates to improvements in carburetors for internal combustion engines, more particularly to means for automatically regulating the choke valve of a carburetor in accordance with the operating condition of the engine to which it is attached.

It is among the objects of this invention to provide means for automatically regulating the choke of carburetors in accordance with the operating requirements of the combustion engine and which shall be adapted to maintain a full choke on the carburetor in starting the engine or when the engine is dead and automatically open the choke valve when the engine is cranked and in operation.

Another object of the invention is to provide means for regulating the speed of opening and closing the choke valve in accordance with atmospheric conditions and temperature.

These and other objects will become more apparent from a consideration of the accompanying drawing in which like reference characters designate like parts and in which Fig. 1 is a side elevational view of an internal combustion engine embodying the principles of this invention; Fig. 2, a detail view of a portion of the carburetor of Fig. 1 illustrating the choke valve and the automatic valve regulating mechanism; Fig. 3, a diagrammatic view of the invention embodying a holding mechanism; and Fig. 4, a side elevational view of a carburetor and choke regulator.

In the drawing 1 designates a cylindrical block of an internal combustion engine; 2 the head; 3 the exhaust manifold; 4 the intake manifold to which a carburetor generally designated at 5 is connected by the flange 6.

Carburetor 5 is provided with the usual pipe line connection 7 leading to a gas tank, a valve control lever 8 connected to the operating mechanism and the air intake 9 having the usual form of butterfly valve or choke 10 pivotally mounted thereon.

It is the object of the butterfly valve to regulate the amount of air employed in the fuel mixture passing to the intake manifold 4 from which it is distributed to the various combustion chambers of the engine. In cranking an engine it is desired to utilize a very rich mixture of gaseous fuel and accordingly the butterfly valve 10 is regulated to choke off the air intake 9 until cranking is effected, when the butterfly valve 10 is immediately opened to permit the ingress of an adequate supply of air to the mixing chamber of the carburetor 1. In accordance with the present invention, the butterfly valve 10 is automatically

regulated to choke off the air supply in cranking the engine and open the butterfly valve after cranking by means of the following mechanism:

A suction device consisting of a cylinder 11 is connected through a line 12 to the intake manifold and is provided with a piston member 13 operatively mounted therein, this piston being movable in a manner hereinafter explained. The butterfly valve 10 is provided with the usual lever arm 14 which, in the present instance, is biased by a coil spring 15 to maintain the position where the valve 10 is vertically disposed which is the full choke position of the carburetor, and lever 14 is connected by a link 16 to the end of the piston rod of piston 13.

In operation, the suction device functions to maintain the valve 10 in the full choke position by action of the spring 15 as long as no suction is available in the intake manifold 4, this being during the idle period of the internal combustion engine. The full choke position is maintained during the cranking of the engine until combustion is effected and the engine is cranked. The operation of the piston member in the internal combustion engine creates suction in the intake manifold 4 and also in the line 12 connecting the choke operating cylinder 11 and when the suction is created in such manner the piston 13 will be drawn in the direction of the suction line 12, pulling lever 14 away from the biased position of spring 15 and subjecting the valve 10 to angular movement whereby the passage of the intake pipe line 9 is open. During the entire operation of the engine the choke valve 10 is maintained in an open position and when the engine is stopped, suction in the line 12 fails, permitting the spring 15 to withdraw the lever 14 and the piston element 13 to the position where valve 10 again resumes the full choke position illustrated in the drawing.

In Figure 2 a modified form of suction device is illustrated and consists of an inflatable rubber member 18, one end of which is connected to the line 12 and the other end by a line 16 to the choke valve lever 14. This mechanism functions precisely as that disclosed in connection with Fig. 1, the member 18 being collapsed when suction is available in the line 12 thereby retarding lever 14 and opening the choke. When the suction fails in line 12 the member 18 assumes its normal expanded position whereby the lever 14 is replaced to the position wherein the butterfly valve 10 is in full choke position. The mechanism shown in Fig. 2 possesses the advantage of not requiring a coil spring such as the spring 110

15 illustrated in Fig. 1, since the member 18 automatically, by expanding, returns the valve operating lever 14 to the choke position.

In both figures 1 and 2 are shown regulating valves 19 which provide for leakage in the suction cylinder 11 in Fig. 1 and the suction line 12 in Fig. 2 for the purpose of regulating the speed of operation of the piston 13, as in Fig. 1 and the element 18 in Fig. 2. By means of these regulating valves, the speed of operating the choke valve can be regulated so that in the winter time the choke will be opened more slowly when conditions are adverse to the rapid starting of the engine, and in summer time the choke operating mechanism can be adjusted to open the choke very quickly after the engine cranks.

In the modification shown in Fig. 3, the valve operating link 16 is provided with an armature 20 that is actuated by a solenoid 21 the winding 20 of which has its terminals 22 and 23 connected to the generator of the engine. In operation after the engine cranks, the armature 20 is brought into engagement with magnet 21 and the latter being energized by the generator will hold link 16 and its attached choke valve 10 in open position as long as the engine is operating. This construction provides against the choke valve 10 closing upon a failure of suction in line 12.

In Fig. 4 the choke regulator is shown connected to the throttle control of the carburetor 5 as a further means of holding the choke 10 in its wide open position when the suction in the engine fails at high speed. In this figure, 25 designates the linkage connecting the foot pedal (not shown) that controls the gas feed of the carburetor, with the control lever 26. A link 27 is connected to lever 14 of the choke, and is in sliding engagement with lever 26. A stop 28 is provided on link 27 which functions to hold the choke 10 in open position when the foot pedal control is set to maximum feed of gas to the engine.

When the engine is operating at high speed the suction in the intake manifold 4 is a minimum and by the engagement of lever 26 with the stop 27 the choke is held open independently of the suction.

It is evident from the foregoing description of this invention that choke regulating means as provided for therein provides simple and expedient means for automatically choking the carburetor in starting the engine and to open its air intake after the engine is in operation.

Although several embodiments of the invention have been herein illustrated and described, it will be obvious to those skilled in the art that various modifications may be made in the details of construction without departing from the principles herein set forth.

I claim:

1. A choking device for carburetors comprising a casing having an air inlet and being in connection with and forming a continuation of the carburetor casing, a choker valve in said first casing, a vacuum chamber in communication with the intake manifold of an engine, and a piston in said vacuum chamber and connected with the choker valve, whereby upon creating a vacuum the choker valve opens, said carburetor including a throttle valve controlling the outlet of said carburetor, and means operatively connecting the throttle valve and the choker valve for control of the latter by the former.

2. The combination with a carburetor including a casing having an air inlet, of a choker valve in said casing, a vacuum chamber in communication with the intake manifold of an engine, a piston in said vacuum chamber and connected with the choker valve whereby upon creating a vacuum, the choker valve opens, said carburetor including a throttle valve controlling the outlet of said carburetor case, and means operatively connecting the throttle valve and the choker valve for control of the latter by the former.

THOMAS N. COFFELDER.
